UNITED STATES PATENT OFFICE.

BENJAMIN F. MAYO, OF SALEM, MASSACHUSETTS, ASSIGNOR TO UNITED SHOE MACHINERY COMPANY, OF PATERSON, NEW JERSEY, A CORPORATION OF NEW JERSEY.

SOLE-PRESSING MACHINE.

No. 861,746.

Specification of Letters Patent.

Patented July 30, 1907.

Application filed October 19, 1903. Serial No. 177,565.

To all whom it may concern:

Be it known that I, BENJAMIN F. MAYO, a citizen of the United States, residing at Salem, in the county of Essex and State of Massachusetts, have invented 5 certain new and useful Improvements in Sole-Pressing Machines; and I do hereby declare the following to be a full, clear, and exact description of the invention, such as will enable others skilled in the art to which it appertains to make and use the same.

10 The present invention relates to sole pressing machines of the so called rolling pressure type in which the sole of a shoe is subjected to a rolling pressure between a last upon which the shoe is supported and a coöperating sole pressing form.

15 A well known form of rolling pressure sole pressing machine is disclosed in the patent to Tripp No. 296,486, dated April 8, 1884. This machine comprises two pivotally mounted last carriers and two coöperating pivotally mounted form carriers, the last and form 20 carriers being so arranged and actuated that when one last carrier and its coöperating form carrier are moved in one direction the other last carrier and its coöperating form carrier are moved in the opposite direction. The mechanism for oscillating the carriers comprises a 25 driving shaft and gearing connecting the driving shaft and the carriers, the direction of rotation of the driving shaft being changed to change the direction of movement of the carriers. All of the carriers are constantly connected with the driving shaft so that when 30 one set of carriers is at the front of the machine with the last in a convenient position for the removal of a shoe therefrom and the placing of another shoe thereon, which position is termed its position of presentation, the other set of carriers is at the rear of the machine. The driving shaft is stopped automatically 35 each time a last reaches a position of presentation and is started into operation by the operator.

In the practical use of the machine the sole of a shoe supported upon a last is subjected to two rolling pressures, one during the backward movement of the last and its coöperating form and the other during their forward movement.

To produce the best results it is desirable to subject the sole of a shoe to a greater number of pressures and 45 a machine has been devised comprising pivotally mounted last and form carriers in which the carriers are oscillated backward and forward a predetermined number of times and then stopped with the last in a position of presentation. In this machine the mechanism for oscillating a last carrier and its coöperating form carrier comprises a crank shaft, a link connecting the shaft and the form carrier and intermeshing segmental gears secured to the form and last carriers, the construction being such that during each revolution

of the crank shaft the form carrier is oscillated backward and forward through the link connection and the last carrier is oscillated from the form carrier through the intermeshing segmental gears. In the practical operation of this machine it has been found that on account of the back lash in the intermeshing segmental 60 gears the last shifts longitudinally with relation to the form as the last and form swing by the line joining the pivotal centers of the carriers, thereby tending to injure the shoe and produce inferior work. Also in this machine the number of pressures to which the sole of 65 a shoe is subjected is predetermined by the construction of the machine so that the operator is unable to vary the number of pressures to suit the quality and thickness of the sole being operated upon.

In the machine comprising last and form carriers 70 which are actuated continuously to subject the sole of a shoe to a plurality of rolling pressures it is desirable to use a crank shaft and intermediate connections for actuating the carriers as thereby the shock and jar and consequent liability of the parts of the machine to 75 wear and injury which would be incident to a construction in which the rotation of a driving shaft such as is disclosed in the Tripp patent was automatically reversed is avoided.

One of the objects of the present invention is, therefore, to provide a sole pressing machine of the rolling pressure type, comprising pivotally mounted last and form carriers, a crank shaft and suitable connections between the shaft and the carriers which shall be free from the sudden and objectional shifting of the last 85 80 with relation to the form incident to the construction above referred to.

A further object of the invention is to provide a sole 90 pressing machine of the rolling pressure type comprising last and form carriers, a crank shaft and suitable connections between the shaft and the carriers in which the number of pressures to which the sole of a shoe is subjected can be varied by the operator to suit the character and thickness of the sole of a shoe being operated upon.

With these objects in view a feature of the present invention contemplates providing a sole pressing machine, comprising pivotally mounted last and form carriers and a crank shaft, with link connections between the crank shaft and both of said carriers whereby 100 the relative movements imparted to the last and form are certain and accurate and the sole of a shoe supported upon the last is pressed in a satisfactory manner without any liability of injury to the shoe.

Another feature of the invention contemplates providing a sole pressing machine comprising last and form carriers, a crank shaft and suitable connections between the crank shaft and the carriers, with means 105

under the control of the operator for throwing the crank shaft out of operation when the last reaches a position of presentation. In the illustrated embodiment of this feature of my invention, hereinafter described, I have provided mechanism under the control of the operator for connecting and disconnecting the crank shaft and a source of power and have provided a cam, driven from the crank shaft and acting on said mechanism to prevent the crank shaft from being disconnected from the source of power until the last reaches its position of presentation. This mechanism in combination with the cam for delaying its operative action until the last reaches its position of presentation I believe to be broadly new and I therefore consider a feature of my invention to consist in providing means under the control of the operator for throwing the actuating mechanism of the last and form carriers of a rolling pressure sole pressing machine out of operation and means for delaying the operative action of such means until the last reaches its position of presentation.

In rolling pressure sole pressing machines as usually constructed the last and form are so actuated that the pressure proceeds longitudinally of the sole of the shoe first from the heel towards the toe and then from the toe towards the heel. This mode of operation tends to crowd the material of the sole towards the toe and heel and to stretch the sole longitudinally. As a result the sole of the shoe is often distorted sufficiently to injure the shoe or even to burst the seam by which the sole is secured to the upper.

One of the objects of the present invention is to provide a sole pressing machine which will operate to press the sole of a shoe without displacing the material of the sole or stretch the sole sufficiently to injure the shoe and with this object in view, a feature of the invention contemplates providing a sole pressing machine comprising form and last carriers with mechanism for actuating said carriers which acts to draw the form over the sole while in contact therewith and preferably in the opposite direction to that in which the pressure is proceeding. By so actuating the carriers the displacing of the material of the sole is prevented and the sole is not stretched longitudinally to any appreciable extent. This feature of the invention broadly considered may be embodied in any rolling pressure sole pressing machine as I believe that I am the first in the art to provide a rolling pressure sole pressing machine comprising a shoe supporting last and a sole pressing form in which the form is drawn over the sole during the pressing operation.

Rolling pressure sole pressing machines as usually constructed are provided with two shoe supporting lasts and two co-operating sole pressing forms and one of the objects of the present invention is to provide a machine of improved construction and mode of operation comprising two shoe supporting lasts and two co-operating sole pressing forms, and more particularly such a machine in which the number of pressing operations to which the sole of a shoe supported upon either last is subjected can be varied at the will of the operator.

With this object in view a feature of the present invention contemplates providing an actuating mechanism for each last carrier and its co-operating form carrier which acts to move the carriers to subject the sole

to a shoe supported upon the last to a plurality of rolling pressures, and means under the control of the operator for throwing one of said actuating mechanisms into operation and for throwing the other actuating mechanism out of operation when the last, actuated by said last mentioned actuating mechanism reaches a position of presentation.

A further object of the invention is to provide a heel clamp of improved construction and mode of operation for holding the heel of the sole upon the last while pressure is being applied to the forepart and with this object in view a feature of the invention consists in the heel clamp hereinafter described and claimed.

In addition to the features of invention above referred to the present invention also consists in certain devices, combinations and arrangements of parts hereinafter described and claimed, the advantages of which will be obvious to those skilled in the art.

In the drawings accompanying this application I have illustrated a rolling pressure sole leveling machine which embodies the various features of my invention in their preferred form, but it is to be understood that except as defined in the claims my invention is not limited to the machine illustrated nor to any particular construction and arrangement of parts.

Referring to the drawings, Figure 1 is a view in side elevation of a rolling pressure sole leveling machine embodying the various features of my invention in their preferred form; Fig. 2 is a rear view of the machine illustrated in Fig. 1; Fig. 3 is a sectional plan view taken on the line 3—3 of Fig. 1; Fig. 4 is a view in front elevation of the lower portion of the machine with certain of the parts shown in section; Fig. 5 is a detail sectional view of the upper end of a link connecting two of the last and form carriers; Fig. 6 is a detail sectional view taken on the line 6—6 of Fig. 5; Fig. 7 is a detail view illustrating the construction and mode of operation of the improved heel clamp; Fig. 8 is a view similar to Fig. 7 showing the parts in a different position, and Fig. 9 is a detail rear view partly in section of a portion of the mechanism illustrated in Fig. 8.

The frame of the machine illustrated in the drawings comprises two vertical front standards 1 and 2 connected at their upper ends by a cross-web 3 and at their lower ends by a cross-web 4. The frame of the machine also comprises the rear standards 5 and 6 which at their upper ends are curved forward and bolted to the front standards. The rear standards 5 and 6 are connected by a cross-web 7 and the front and rear standards are connected near their lower ends by a cross-web one of which is indicated at 8 in Fig. 1. At each side of the machine a casting 9 is fitted to the front and rear standards and is secured in position by bolts. A bracket 10 is bolted upon the upper surface of the cross-web 7 connecting the two rear standards and a web 11 connects the webs 7 and 4 and is bolted at each end to said webs.

Beneath the cross-web 3 of the machine frame are pivotally mounted two form carriers 12 and 13 upon which the sole pressing forms are yieldingly mounted in a well known manner. Beneath the form carriers two last carriers 14 and 15 are pivotally mounted, the pivot rod of these carriers being supported in brackets extending inwardly from the side standards 1 and 2 and in a central standard extending upwardly from

the cross-web 4. Shoe supporting lasts are secured to these carriers in the usual manner and the carriers are so arranged with relation to each other that when the carriers are oscillated the soles of shoes supported upon them are subjected to a rolling pressure.

For actuating each last carrier and its co-operating form carrier a separate mechanism is provided, each of which mechanisms comprises a crank shaft 16. The inner ends of the crank shafts 16 are journaled in bearings in the web 11 and the outer ends of the shafts are journaled in the castings 9 as is clearly illustrated in Figs. 3 and 4. The shafts are arranged in alignment with each other but rotate independently. Each crank shaft is provided with a crank 17 which is connected by a link 18 to one of the last carriers. Each last carrier is thus connected to its crank shaft by a link connection so that during a single revolution of the crank shaft the last carrier is oscillated backwards and forwards. In order to cause the form carriers to be oscillated in timed relation with the last carriers, each last carrier and its co-operating form carrier are connected by a link 19, the lower end of the link being pivotally connected to the last carrier by the pivot pin which connects the carrier to the link 18 and the upper end of the link 19 being pivotally connected to the form carrier on the opposite side of the pivotal center of the carrier. Both the last carriers and the form carriers are thus connected by means of links to the cranks of the crank shafts 16, the last carriers being directly connected by the links 18 and the form carriers being connected by the links 19, the last carriers and the links 19. The oscillating movements which are imparted to the last and form carriers from the crank shafts are, therefore, certain and accurate and any relative movement of the lasts and forms when the carriers swing by the line joining the pivotal centers of the carriers which would tend to injure the shoe is prevented.

The relative angular positions of the pivotal connections of the links 18 and 19 with the last and form carriers and the distances of these pivotal connections from the pivotal centers of the carriers, are such, that when a form carrier is oscillated from a last carrier through a connecting link 19 the surface of the form is in contact with the sole travels faster than the surface of the sole, so that the form is drawn over the sole during the pressing operation in the opposite direction to that in which the pressure is proceeding. As a result of this drawing action of the form, the displacing of the material which would otherwise take place is prevented and the sole is pressed without any liability of injury to the shoe or any appreciable stretching of the sole longitudinally. The manner in which the links 19 are connected to the form carriers is clearly illustrated in Figs. 5 and 6. As shown in these figures, the upper end of the link 19 illustrated is provided with a cylindrical bearing which engages a sleeve 20 eccentrically mounted upon a stud 21 secured in a form carrier. In this construction there is no lost motion between the link and the form carrier, so that the link forms a rigid connection between the form carrier and the last carrier and acts to positively actuate the form carrier in both directions. With this construction, therefore, a drawing movement is imparted to the form during the movements of the carriers in both

directions, the form being drawn over the sole towards the heel while the pressure is proceeding from the heel towards the toe and being drawn over the sole towards the toe while the pressure is proceeding from the toe towards the heel. The sleeve 20 can be rotated about the stud 21 and secured in adjusted position by turning up the nuts which secure the stud in the carrier. By so rotating the sleeve, the upper end of the link is moved towards or from the pivotal center of the carrier, and thus the amount of the drawing movement which is imparted to the form is adjusted as desired.

Each crank shaft 16 is provided with a worm gear 25 which is engaged by a worm 26 upon a shaft 27 journaled in bearings in a casting 9. Each shaft 27 is provided at its rear end with a frictional clutch member 28 secured to the shaft and with a driving pulley 29 mounted to rotate loosely on the shaft. The driving pulleys are provided with frictional surfaces to engage the frictional clutch members 28 and means are provided for moving the pulleys longitudinally of the shafts 27 independently of each other so that each shaft 27 and the crank shaft geared thereto can be driven separately. Both pulleys 29 are rotated constantly by means of a single driving belt 30 which passes over the pulleys and over an intermediate idler pulley 31 mounted upon a stud secured in the bracket 10. The driving pulleys are moved into and out of engagement with their clutch members and their movements are controlled by means which are substantially duplicates of each other, and in the following description I have accordingly referred to the means for moving but one pulley longitudinally of its shaft and for controlling its movements, it being understood that except as otherwise specified the parts referred to are duplicated on opposite sides of the machine.

The driving pulley 29 at the right hand side of the machine is rigidly secured to a sleeve 32 provided with a groove which is engaged by studs projecting from the forked upper end of one arm of a lever 33 loosely pivoted upon a shaft 34 extending across the rear of the machine and journaled in bearings in the castings 9. The other arm of the lever 33 is connected by an adjustable link 35 to the rear end of a lever 36, the construction and arrangement of the levers 33 and 36 and the link 35 being such that when the rear end of the lever 36 is raised the pulley 29 is moved into engagement with the clutch member 28 and when the rear end of the lever 36 is depressed the pulley is moved out of engagement with the clutch member. The rear end of the lever 36 is provided with an anti-friction roll which is engaged by a cam 37 secured to the rear end of a rock shaft 38 journaled in bearings in a casting 9 and in a bracket secured to one of the front standards of the machine frame. To the front end of the shaft 38 a treadle lever 39 is secured by means of which the shaft 38 and cam 37 secured thereto can be rocked by the operator. The shape of the cam 37 is such that when the treadle 39 is depressed by the operator the high part of the cam is caused to engage the anti-friction roll of the lever 36 and raise the rear end of the lever, thereby actuating the lever 33 to move the pulley 29 into engagement with the clutch member 28. The pulley remains locked in engagement with the clutch member until the cam 37 is oscillated in the opposite direction.

the shape and arrangement of the cam 37 being such that it remains in the position to which it is moved by the operator. The crank shaft 16 on the right hand side of the machine is thus thrown into operation and 5 continues to rotate until the cam 37 is moved by the operator to release the lever 36 so that the sole of the shoe being operated upon can be subjected to any desired number of pressures. When the cam 37 is moved to release the lever 36 the lever 36 is moved in a direction to cause the driving pulley to be moved out of engagement with the clutch member 28 by means of a coiled spring 40, one end of which is attached to the frame of the machine and the other end to the front end of the lever 36. In order to prevent the lever 36 from 10 being actuated by this spring 40 until the last and form carriers which are being actuated are returned to a position at the front of the machine a cam 41 is secured to the outer end of the shaft 16 and arranged to engage a roll upon the front end of the lever 36. This cam is so 15 shaped that the front end of the lever 36 is held depressed against the tension of the spring 40 after the lever has been released by the cam 37 until the last and form carriers which are in operation are returned to a position at the front of the machine when the front 20 end of the lever is released by the cam and the spring 40 allowed to act to move the driving pulley 29 out of engagement with the clutch member 28.

In the operation of the machine the actuating mechanisms of the two sets of last and form carriers are 25 thrown into operation alternately, one last and form carrier remaining at rest at the front of the machine while the other last and form carrier are being actuated to press the sole of a shoe. In order to cause one set of last and form carriers to come to rest at the front of the 30 machine when the other set of last and form carriers are thrown into operation, the two cams 37 on the opposite sides of the machine are connected by a rod 42 so that when one cam is moved to raise the outer end of one of the levers 36 the other cam 37 is moved to release the 35 other lever 36. The act of the operator in throwing the actuating mechanism of one set of last and form carriers into operation thus causes the mechanism of the other set of last and form carriers to be thrown out of operation when the carriers are returned to the front of the 40 machine and the last reaches its position of presentation.

It will be noted that the last and form carriers which are at rest at the front of the machine can be thrown into operation at any time during the movements of the 45 last and form carriers which are in operation so that the operator after having placed a shoe upon the last which is in a position of presentation is not obliged to wait until the other last is returned to its position of presentation before throwing the last and form carriers which 50 are at the front of the machine into operation. If it is desired to bring the last and form carriers which are in operation to rest at the front of the machine without throwing the other last and form carriers into operation this can be accomplished by moving the cams 37 sufficiently to remove the high portion of one cam from engagement with a lever 36 but not sufficiently to bring the high part of the other cam 37 into engagement with the other lever 36.

It is sometimes necessary to throw the actuating 55 mechanism of the last and form carriers out of operation

before they reach their position at the front of the machine as for instance to prevent crushing the hand of an operator caught between a last and form. The machine illustrated in the drawings is accordingly provided with means whereby the actuating mechanism of the last and form carriers in operation can be thrown out of operation at any point in their movement. These means comprise yoke-shaped arms 43 secured to the shaft 34 and straddling the bearings in the castings 9 for the shaft, links 44 connecting the arms 43 with the links 35, pin and slot connections between the upper ends of the links 35 and the levers 33, an arm 45 secured to the shaft 34 and a pull rod 46, the rear end of which is pivotally connected to the upper end of the arm 45, and the forward end of which extends into a convenient position to be grasped by the operator. The construction and arrangement of these parts is such that when the rod 46 is pulled forward the shaft 34 is rocked in a direction to move the upper ends of the links 35 rearwardly in the slots in the levers 33. This movement of the upper ends of the links 35 swings the levers 33 which, as has been stated, are loosely mounted upon the shaft 34 in a direction to move the pulleys 29 out of engagement with the clutch members 28 so that whenever the rod 46 is pulled forward the actuating mechanism of the last and form carriers which are being operated to press the sole of a shoe, is immediately thrown out of operation.

In order to stop the rotation of the shaft 27 as soon as the driving pulley 29 is disconnected from the clutch member 28, either by the movement of the rod 46 or by the movement of the lever 36, a brake disk 47 is secured to the shaft 27 and arranged to be engaged by a brake shoe 48. The brake shoe 48 is pivotally mounted at the joint of a toggle 49, one arm of which is pivotally connected to the lever 33, and the other arm of which is pivotally connected to a casting 9. The arms of the toggle are so arranged that when the lever 33 is moved in a direction to disconnect the pulley 29 from the clutch member 28 the brake shoe 48 is pressed against the periphery of the brake disk 47. A coiled spring 50 connects the lever 33 with the casting 9 and tends to move the lever to disengage the driving pulley from the clutch member.

The improved heel clamp which I have provided for holding the heel portion of the sole upon the last while pressure is being applied to the forepart is clearly illustrated in Figs. 7, 8 and 9. In these figures 51 indicates a clamp arranged to extend over and bear upon the heel portion of the sole. This clamp is secured to the upper end of a rod 52 mounted to slide through blocks 53 and 54 swiveled in the upper and lower ends of an arm 55 pivotally mounted upon a last carrier. The rod 52 is bent above the block 53 as illustrated in Fig. 2 to bring the clamp in line with the last and is also bent between the blocks 53 and 54 as shown in Figs. 7 and 8, the purpose of the last mentioned bend being to impart additional rearward and forward movements to the clamp when the rod 52 is raised and lowered as will be hereinafter described. To the lower end of the rod 52 is secured a block 56 to which is pivoted a block 57 provided with a roll 58 arranged to engage the surface of a cam plate 59 adjustably secured to the last carrier. The block 56 is connected by means of a chain 59 to one of the front standards of the machine.

frame and the upper end of the arm 55 is connected to one of the front standards of the machine frame by means of a coiled spring 60. A spring 61 is coiled around the rod 52 and bears at its upper end against the block 53 and at its lower end against a collar 62 secured to the rod. When the form carrier is in the position illustrated in Fig. 7 with the last in its position of presentation, the arm 55 is held in the position illustrated by means of the chain 59, the spring 60 being stretched and the rod 52 being held in its raised position by the engagement of the roll 57 with the cam plate 58. As the form carrier swings rearwardly the spring 60 swings the arm 55 about its pivot and the spring 61 lowers the rod 52 until the clamp 51 is brought into contact with the sole of the shoe, the downward movement taking place as the roll 57 travels along the cam plate 58. The clamp 51 remains in contact with the sole during the continued rearward movement of the last carrier and also during the return forward movement of the last carrier until the chain 59 is again tightened. As the carrier swings to its position at the front of the machine the arm 55 is swung about its pivot against the tension of spring 60 and the roll 57 is caused to travel along the cam plate 58, thereby returning the clamp to the position illustrated in Fig. 7. The bent portion of the rod 52 between the blocks 53 and 54 causes an additional rearward movement of the clamp during its upward movement and a corresponding additional forward movement during its downward movement, these additional movements being sufficient to cause the clamp to be actuated at the desired times during the movements of the last and form carriers without contacting with the form. The block 56 has a limited swinging movement with relation to the block 56^a and rod 52, being swung into a position in line with the rod 52 when the chain 59 is tightened and being swung into a position inclined to the rod when the chain 59 is slack. An initial upward movement is thus imparted to the rod 52 to raise the clamp 51 from the sole before the arm 55 is swung to move the clamp away from the last, and a final downward movement to press the clamp against the sole after the clamp has been inserted between the last and form.

The operation of the machine above described has been sufficiently indicated in connection with the description of the construction and arrangement of the various parts and will be readily understood by those skilled in the art without a separate description thereof.

Having thus indicated the nature and scope of my invention and having specifically described a machine embodying the various features thereof in their preferred form, I claim as new and desire to secure by Letters Patent of the United States:

1. A sole pressing machine, having, in combination, a shoe supporting last, a sole pressing form, a pivotally mounted last carrier, a pivotally mounted form carrier, and mechanism for oscillating the last and form carriers to subject the sole of a shoe supported upon the last to a rolling pressure comprising a crank shaft, and link connections between said crank shaft and both of said carriers, substantially as described.
2. A sole pressing machine, having, in combination, a shoe supporting last, a sole pressing form, a pivotally mounted last carrier, a pivotally mounted form carrier, and mechanism for oscillating the last and form carriers to subject the sole of a shoe supported upon the last to a rolling pressure comprising a crank, a link connecting
3. A sole pressing machine, having, in combination, a shoe supporting last, a sole pressing form, a last carrier, a form carrier, and mechanism for actuating said carriers to subject the sole of a shoe supported upon the last to a rolling pressure acting to draw the form over the sole while in contact therewith, substantially as described.
4. A sole pressing machine, having, in combination, a shoe supporting last, a sole pressing form, a last carrier, a form carrier, and mechanism for actuating said carriers to subject the sole of a shoe supported upon the last to a rolling pressure acting to move the surfaces of the form and sole at different speeds, substantially as described.
5. A sole pressing machine, having, in combination, a shoe supporting last, a sole pressing form, a last carrier, a form carrier, mechanism for positively actuating both of said carriers to subject the sole of a shoe supported upon the last to a rolling pressure acting to impart a greater speed to the surface of the form than to the surface of the sole, substantially as described.
6. A sole pressing machine, having, in combination, a shoe supporting last, a sole pressing form, a last carrier, a form carrier, and mechanism for actuating said carriers to subject the sole of a shoe supported upon the last to a rolling pressure acting to draw the form over the sole while in contact therewith said mechanism having provision for adjustment to vary the amount of the drawing movement, substantially as described.
7. A sole pressing machine, having, in combination, a shoe supporting last, a sole pressing form, a last carrier, a form carrier, and mechanism for actuating said carriers to subject the sole of a shoe supported upon the last to a rolling pressure acting to draw the form over the sole while in contact therewith, substantially as described.
8. A sole pressing machine, having, in combination, a shoe supporting last, a sole pressing form, a last carrier, a form carrier, a crank shaft and suitable connections for actuating said carriers to subject the sole of a shoe supported upon the last to a plurality of rolling pressures and means under the control of the operator for throwing said crank shaft out of operation when the last reaches a position of presentation, substantially as described.
9. A sole pressing machine, having, in combination, a shoe supporting last, a sole pressing form, a last carrier, a form carrier, a crank shaft and suitable connections for actuating said carriers to subject the sole of a shoe supported upon the last to a plurality of rolling pressures, mechanism controlled by the operator for connecting and disconnecting said crank shaft and a source of power, and a cam acting on said mechanism to prevent the crank shaft from being disconnected from the source of power until the last reaches a position of presentation, substantially as described.
10. A sole pressing machine, having, in combination, a shoe supporting last, a sole pressing form, a last carrier, a form carrier, a crank shaft and suitable connections for actuating said carriers to subject the sole of a shoe supported upon the last to a rolling pressure, mechanism controlled by the operator for connecting and disconnecting said crank shaft and a source of power, and means for preventing the crank shaft from being disconnected from the source of power until the last reaches a position of presentation, substantially as described.
11. A sole pressing machine, having, in combination, a shoe supporting last, a sole pressing form, a last carrier, a form carrier, mechanism for actuating said carriers to subject the sole of a shoe supported upon the last to a plurality of rolling pressures, means under the control of the operator for throwing said mechanism out of operation, and means for delaying the operative action of said means until the last reaches its position of presentation, substantially as described.
12. A sole pressing machine, having, in combination, two shoe supporting lasts, two co-operating sole pressing forms, a last carrier for each last, a form carrier for each form,

an actuating mechanism for each last carrier and its co-operating form carrier acting to move the carriers to subject the sole of a shoe supported upon the last to a plurality of rolling pressures, and means controlled by the operator for throwing one of said actuating mechanisms into operation and for throwing the other actuating mechanism out of operation when the last actuated thereby reaches a position of presentation, substantially as described.

13. A sole pressing machine, having, in combination, two shoe supporting lasts, two co-operating sole pressing forms, a last carrier for each last, a form carrier for each form, two independently rotatable crank shafts and suitable connections for actuating said carriers to subject the soles of shoes supported upon the lasts to a plurality of rolling pressures, mechanism controlled by the operator for connecting one of said crank shafts to a source of power and for disconnecting the other therefrom, and means for preventing the crank shaft in operation from being disconnected from the source of power until the last actuated thereby reaches a position of presentation, substantially as described.

14. A sole pressing machine, having, in combination, a shoe supporting last, a sole pressing form, a pivotally mounted last carrier, a form carrier, means for actuating said carriers to subject the sole of a shoe supported upon the last to a rolling pressure, an arm pivotally mounted upon the last carrier, blocks pivotally mounted on the arm, a rod mounted to reciprocate through said blocks provided with a bend between the blocks, a clamp carried by the rod, a spring acting to swing the arm to move the clamp towards the last during the movement of the last carrier in one direction, means for swinging the arm to move the clamp away from the last during the movement of the last carrier in the opposite direction, a cam on the last carrier acting to reciprocate the rod to raise the clamp as it is moved away from the last and a spring acting to reciprocate the rod to lower the clamp as it is moved towards the last, substantially as described.

15. A sole pressing machine, having, in combination, a shoe supporting last, a sole pressing form, a pivotally mounted last carrier, a form carrier, means for actuating said carriers to subject the sole of a shoe supported upon the last to a rolling pressure, an arm pivotally mounted upon the last carrier, a rod mounted to reciprocate on the arm, a clamp carried by the rod, means for swinging the arm to move the clamp towards the last during the movement of the last carrier in one direction and to move the clamp away from the last during the movement of the last carrier in the opposite direction, a cam on the last carrier acting to reciprocate the rod to raise the clamp as it is moved away from the last and a spring acting to reciprocate the rod to lower the clamp as it is moved towards the last, substantially as described.

16. A sole pressing machine, having, in combination, a shoe supporting last, a sole pressing form, a pivotally mounted last carrier, a form carrier, means for actuating said carriers to subject the sole of a shoe supported upon the last to a rolling pressure, an arm pivotally mounted upon the last carrier, blocks pivotally mounted on the arm, a rod mounted to reciprocate through said blocks provided with a bend between the blocks, a clamp carried by the rod, means for swinging the arm to move the clamp towards the last during the movement of the last carrier in one direction and to move the clamp away from the last during the movement of the last carrier in the opposite direction, and means for reciprocating the rod to raise the clamp as it is moved away from the last and to lower the clamp as it is moved towards the last, substantially as described.

In testimony whereof I affix my signature, in presence of 70 two witnesses.

BENJAMIN F. MAYO.
